(57) **CLAIM**

The ornamental design for a garment adjuster, as shown and described.

DESCRIPTION

FIG. 1 is a top perspective view of the garment adjuster of the instant invention;

FIG. 2 is a left side view thereof;

FIG. 3 is a right side view thereof;

FIG. 4 is a top view thereof;

FIG. 5 is a bottom view thereof;

FIG. 6 is a right side view thereof;

FIG. 7 is a left side view thereof; and,

FIG. 8 is a front view illustrating the instant invention secured within the waistband of a pair of pants.

The portions of the figures illustrated in broken lines are for illustrative purposes only and form no part of the claimed design.
